I. MARINO

INDICATOR

Filed May 8, 1923

Inventor
I. Marino
J. N. Bryant,
Attorney.

UNITED STATES PATENT OFFICE.

IGNAZIO MARINO, OF WASHINGTON, DISTRICT OF COLUMBIA.

INDICATOR.

Application filed May 8, 1923. Serial No. 637,539.

To all whom it may concern:

Be it known that I, IGNAZIO MARINO, a subject of the King of Italy, residing at Washington, in the District of Columbia, have invented certain new and useful Improvements in Indicators, of which the following is a specification.

This invention relates to certain new and useful improvements in indicators and particularly to that type designed for use in hotels or offices for indicating the whereabouts of different persons, indicating whether or not they are in their hotel or offices, absent therefrom, sick and the time when their return is expected.

The primary object of the invention resides in the provision of an indicator casing adapted for mounting upon a wall board or other support permitting a plurality of indicator casings to be so mounted with the indicator casing so constructed to permit the substitution of desired name cards whenever desired.

A further object of the invention is to provide an indicator embodying a pair of rollers carrying indicia upon the peripheries thereof with a novel means of rotatably supporting the rollers within the indicator casing.

With the above and other objects in view as the nature of the invention is better understood, the same consists of the novel form, combination and arrangement of parts hereinafter more fully described, shown in the accompanying drawing and claimed.

In the drawing, wherein like reference characters designate corresponding parts throughout the several views,

Figure 1 is a perspective view of an indicator constructed in accordance with the present invention, the mounting board being illustrated as supporting a single indicator casing.

Figure 2 is a top plan view of the inner block of the indicator member showing the separate pocket in which the indicia carrying rollers are journaled,

Figure 3 is a horizontal sectional view taken through the indicator showing the indicator rollers journaled therein, the rollers being journaled in the inner block and removable casing,

Figure 4 is an end elevational view of one end of the inner block,

Figure 5 is an end elevational view of the other end of the block,

Figure 6 is a vertical cross-sectional view of the indicator and a portion of the mounting board therefor, and

Figure 7 is a longitudinal sectional view of one of the indicator rollers.

Referring more in detail to the accompanying drawing, the indicator casing is illustrated as removably mounted upon a supporting wall board or other hanger, the wall board 1 being centrally and longitudinally grooved as at 2 with the opposite side walls of the groove inclined as at 3 to form a dove-tailed-shaped slot while edge strips 4 are secured to the front face of the board 1 forming a frame structure, the upper strip 4^a being removably secured to the board to permit mounting of the indicator casing as hereinafter described.

The indicator includes a block 5 carrying a dove-tailed-shaped plug 6 upon the bottom face thereof adapted for sliding and interlocking engagement in the slot 2 of the mounting board 1, the lower side of the block 5 being cutaway as at 7 and 8 to provide arcuate cavities or pockets 9 and 10 that are separated by the partitions 11 arranged adjacent one end of the block forming a relatively long pocket 9 and a relatively short pocket 10, the pockets 9 and 10 opening at the lower ends of the upper sides of the slot 5 and also at the lower end thereof. The upper face of the block 5 is longitudinally grooved as at 12 providing spaced ribs 13 as clearly shown in Figs. 4 to 6.

A transparent glass plate 14 is mounted on the upper face of the block, the same being supported by the ribs 13 and adjacent edge of the partition 11 and is retained in position thereon by a casing having an outer wall 15, end walls 16 and 17 and upper and lower walls 18, the upper and lower and end walls engaging the block 5 as shown in Fig. 6, the outer wall 15 of the casing enclosing the sides and ends of the block 5 and abutting the transparent glass plate 14. The casing wall 15 is provided with a longitudinally extending opening 19 adjacent the upper end thereof that is aligned with the groove 12

in the upper face of the block 5, the lower end of the casing wall 15 being provided with a longitudinally extending opening 20 aligned with the pocket 9 while a third relatively short opening 21 in the casing wall 15 registers with the pocket 10. The end wall 16 of the casing has a slotted opening 22 formed therein that registers with the groove 12 in the block 5 for purposes presently to appear.

Rollers 23 and 24 are journaled in the pockets 9 and 10 respectively, each roller carrying an axial bearing pin 25 at one end thereof that is journaled in the partition 11 while the opposite end of each roller has a threaded opening 26 formed axially thereof, the end of each roller 23 and 24 having the threaded socket 26 being provided with an eccentric opening 27. Pivotting and operating screw buttons 28 have the threaded shanks thereof passing through the end walls 16 and 17 of the casing to be threaded into the sockets 26 with the rollers 23 and 24 journaled in the partition 11 and end walls 16 and 17. In mounting the screw button 28, a pin is passed through an opening 30 in the end walls of the casing and enters the openings 27 in the rollers 23 and 24, holding the rollers stationary during the mounting of the screw buttons 28 and also for holding the rollers against movement when the screw buttons are removed whenever desired. The roller 23 is provided with suitable indicia 23^a, such as Sick, In, Out—Return, while the roller 24 is provided with indicia 24^a indicating time, a name card 31 being inserted through the slot 22 in the end wall 16 of the casing to be received in the groove 12 and viewable through the casing opening 19, the rollers 23 and 24 being disposed rearwardly of the openings 20 and 21 in the casing cover 15 as clearly shown in Fig. 1.

From the above detail description of the device, it is believed that the construction and operation thereof will at once be apparent, it being noted that the indicator is especially adapted for use in hotels, offices or similar places, the mounting board 1 being of a size to carry a plurality of indicator casings that are removably interlocked therewith with each indicator being independently operable as above described. The rollers 23 and 24 are independently rotatable and to remove the same from the indicator casing and block, the rollers are retained against movement by a key or pin entering the registering openings 27 and 30 in the rollers and end walls of the casing, holding the rollers stationary while the screw buttons 28 are removed therefrom, the screw buttons forming end bearings for the rollers and also locking the rollers and casing to the block 5.

While there is herein shown and described

the preferred embodiment of the present invention, it is nevertheless to be understood that minor changes may be made therein without departing from the spirit and scope of the invention as claimed.

70

What is claimed as new is:

1. In an indicator of the type described, a block having pockets formed therein, a removable casing enclosing said block having openings therein with certain ones of the openings overlying said pockets, indicia carrying rollers in the pockets journaled in the block and casing, a name plate removably supported by the block and viewable through one of the casing openings, the roller journals supported by the casing constituting rotating means for the rollers which are separable from both the casing and roller, said casing having apertures therein adjacent the outer ends of the rollers and said rollers each having an opening in its outer end adapted for the reception of a key when the casing and roller apertures are aligned to permit disconnection of the journals at the outer ends of the rollers from the said rollers and casing.

2. In an indicator of the type described, a block, a removable casing enclosing the block, rollers journaled at their ends in the block and casing with the journals between the rollers and casing forming an interlocking connection between the block and casing and embodying screw buttons journaled in the casing and threaded in adjacent ends of the rollers.

3. In an indicator of the type described, a block, a removable casing enclosing the block, rollers journaled at their ends in the block and casing with the journals between the rollers and casing forming an interlocking connection between the block and casing and embodying screw buttons journaled in the casing and threaded in adjacent ends of the rollers, said casing and adjacent ends of the rollers having openings therein adapted to aline upon rotation of the rollers for the reception of a key to retain the rollers stationary for permitting removal of the screw buttons and separation of the casing from the block.

4. In an indicator of the type described, a block, a removable casing enclosing the block, rollers journaled at their ends in the block and casing with the journals between the rollers and casing forming an interlocking connection between the block and casing and embodying screw buttons journaled in the casing and threaded in adjacent ends of the rollers, said casing and adjacent ends of the rollers having openings therein adapted to aline upon rotation of the rollers for the reception of a key to retain the rollers stationary for permitting removal of the screw buttons and separation of the casing from the block, said block having a

- groove portion in the outer face thereof, the casing having openings therein part of which expose the rollers and block groove, one of said rollers carrying information such as "In," "Out—Return," "Busy—Until," and "Sick," another roller carrying time characters and a name plate removably positioned in the groove through one of the openings in the casing.
- 5 5. In an indicator of the type described, a block cutaway to provide spaced pockets separated by a partition which forms an integral part of the block, a removable casing enclosing the block, indicia carrying rollers journaled in the partition and end walls of the casing forming an interlocking connection between the block and casing, said casing having openings therein part of which expose the rollers, and a name plate removably positioned to be supported by the block through one of the casing openings and viewable through another of the casing openings.
- 10 In testimony whereof I affix my signature.

IGNAZIO MARINO.
